UNITED STATES PATENT OFFICE.

MARY TURNER, OF NEW YORK, N. Y., ASSIGNOR TO THE BUTTERICK PUBLISHING COMPANY, (LIMITED,) OF SAME PLACE.

DESIGN FOR A MISS'S COSTUME.

SPECIFICATION forming part of Design No. 14,832, dated February 26, 1884.

Application filed January 23, 1884. Term of patent 3½ years.

To all whom it may concern:

Be it known that I, MARY TURNER, of the city, county, and State of New York, have invented and produced a new and original Design for a Pattern of a Miss's Costume, (numbered 9,041;) and I do hereby declare that the engraved prints accompanying this specification convey to any one accustomed to using paper patterns a clear understanding of how a garment made up by the pattern will appear.

The design shows a round skirt with a short front drapery that displays three cross-plaits; closely-fitted vest-fronts with buttons all the way down; shorter jacket-fronts rounding away from the neck; a closely-fitted polonaise-

back, presenting an oval outline at the bottom, and displaying under-folded plaits at the lower ends of its seams, and loopings in the front edges; coat-sleeves, and a standing collar.

What I claim as my invention, and desire to secure by Letters Patent, is -

The design for a miss's costume, as shown in the engraved prints accompanying this specification.

MARY TURNER.
